US00D760646S

(12) **United States Design Patent**
Walker(10) **Patent No.:** **US D760,646 S**
(45) **Date of Patent:** **** Jul. 5, 2016**(54) **RECHARGEABLE BATTERY UNIT**

- (71) Applicant: **Deben Group Industries Limited**,
Melton, Woodbridge (GB)
- (72) Inventor: **Stephen Andrew Walker**, Ipswich (GB)
- (73) Assignee: **Deben Group Industries Limited**,
Woodbridge (GB)
- (**) Term: **14 Years**
- (21) Appl. No.: **29/518,587**
- (22) Filed: **Feb. 25, 2015**

Primary Examiner — Deanna L Pratt*Assistant Examiner* — Sanjeev Paul(74) *Attorney, Agent, or Firm* — Hayes Soloway, P.C.(57) **CLAIM**

I claim the ornamental design for a rechargeable battery unit, as shown and described.

DESCRIPTION

FIG. 1 is a front perspective view of a rechargeable battery unit showing the new design;

FIG. 2 is a front view of the rechargeable battery unit thereof;

FIG. 3 is a back view of the rechargeable battery unit thereof;

FIG. 4 is a left side view of the rechargeable battery unit thereof;

FIG. 5 is a right side view of the rechargeable battery unit thereof;

FIG. 6 is a top plan view of the rechargeable battery unit thereof;

FIG. 7 is a bottom view of the rechargeable battery unit thereof; and,

FIG. 8 is a back perspective view of the rechargeable battery unit thereof.

1 Claim, 8 Drawing Sheets(56)
